United States Patent

Des. 238,312
Patented Dec. 30, 1975

238,312

JEWELRY BOX OR SIMILAR ARTICLE

Robert S. Witkoff, Glen Cove, Long Island, N.Y., assignor to The Alsten Company

Filed Sept. 3, 1974, Ser. No. 502,504

Term of patent 14 years

Int. Cl. D3—99

U.S. Cl. D87—1 B

FIG. 1

FIG. 2

FIG. 3

FIG. 4

FIG. 5

FIG. 6

FIG. 1 is a top, front perspective view of a jewelry box embodying my new design;

FIG. 2 is a bottom rear perspective view thereof;

FIG. 3 is a bottom plan view;

FIG. 4 is a top, front perspective view in display position with the bottom case and cover being inverted and the front of the cover flush with and aligned with the rear face of the bottom case;

FIG. 5 is a bottom, rear perspective view thereof; and

FIG. 6 is a bottom plan view.

I claim:

The ornamental design for a jewelry box or similar article, substantially as shown.
